(57) **CLAIM**

What is claimed is the ornamental design for a communication tablet cradle and charger, as shown and described.

DESCRIPTION

FIG. 1 is a perspective front view of a communication tablet cradle and charger showing an embodiment of a new design; FIG. 2 is a perspective front view of the ornamental design of FIG. 1 engaged with a communication tablet;

FIG. 3 is a perspective front view of the ornamental design of FIG. 1 disengaged from the communication tablet;

FIG. 4 is a left side elevation view of the ornamental design of FIG. 1;

FIG. 5 is a right side elevation view of the ornamental design of FIG. 1;

FIG. 6 is a front elevation view of the ornamental design of FIG. 1;

FIG. 7 is a rear elevation view of the ornamental design of FIG. 1;

FIG. 8 is a top plan view of the ornamental design of FIG. 1; and,

FIG. 9 is a bottom plan view of the ornamental design of FIG. 1.

The portions shown in broken lines are for illustrative purposes only and form no part of the claimed design.
